PROJECTILE FOR FIREARMS

George Norman Alibree, Winchester, Mass.

Application September 5, 1941, Serial No. 409,648

14 Claims. (Cl. 102—50)

This invention relates to projectiles for guns.

Among the objects of the invention are to provide a projectile which will have a decreased air resistance and consequently an increased sustained velocity; to provide a projectile which, when assembled with a cartridge case containing explosive material will form a round of ammunition that has the same external dimensions, configuration and appearance as a standard round of the same caliber and can, therefore, be used in any gun interchangeable with standard rounds of ammunition, which projectile has the capacity of changing its shape from one having a given ballistic form to one having a better or superior ballistic form between the time it is loaded into a gun and the time that it is discharged therefrom; to provide a projectile in which the point or tip of the nose is concavely curved in the direction of its length, and is formed by a piece which is separate from the body of the projectile; to provide a projectile which, when discharged, will have a reduced yaw or spiral motion after it leaves the barrel of the gun, and will "go to sleep" at a much earlier point in its trajectory than standard projectiles now commonly used; to provide a projectile which is constructed so that the flow of air around the projectile during flight will have a propelling effect on the projectile, thus augmenting the sustained velocity; to provide a projectile which is constructed so that a decreased amount of the kinetic energy of the projectile is converted into sound waves, whereby an increased amount of such energy is available for continuing the flight of the projectile; and to improve projectiles for firearms in other respects as will be hereinafter pointed out.

In the accompanying drawing, the invention is illustrated as applied to .50 caliber projectile, but I wish to state that the invention is not restricted to any particular caliber nor to a projectile that is seated in a "case."

Fig. 1 is a side view of a cartridge case loaded with my improved projectile.

Fig. 2 is a longitudinal sectional view thereof.

Fig. 3 is a sectional view of the projectile after ignition of the charge, and showing the change in the shape of the projectile which has taken place automatically.

Fig. 4 is a fragmentary sectional view of a cartridge loaded with a projectile embodying the invention but having a different form from that shown in Figs. 2 to 3.

Fig. 5 is a sectional view of the projectile shown in Fig. 4 and illustrating its changed shape.

Fig. 6 is a section on the line 6—6, Fig. 3.

Fig. 7 is a view illustrating the extensible nose tip and its stem before it is assembled with the body of the projectile, the curvature of the stem being somewhat exaggerated.

Fig. 8 is a fragmentary sectional view showing a different embodiment of the invention.

10 In the drawing, 1 indicates a cartridge case of the conventional form in the neck 20 of which is seated a projectile 2 embodying my invention, said cartridge case having the usual primer-receiving pocket 3 in its base containing a primer 15 4 of any approved construction, and also having the usual flash hole 5 leading from the primer-receiving pocket 3 to the interior chamber 6 containing the charge 7.

One feature of my invention relates to a projectile which, when assembled with a cartridge case containing explosive material, forms a round of ammunition that has the dimensions, configuration and outward appearance of a standard round of the same caliber, but which 20 is constructed so that it will develop considerably less air resistance during flight than projectiles of standard rounds of ammunition. Such decrease in air resistance is secured by making the projectile so that during its flight it has a sharp 25 pointed nose of special construction in which the tip end of the nose preferably has a concave curvature in the direction of the length of the projectile that merges into and forms a continuation of the surface of the base portion of the nose.

While a projectile having a nose which terminates in a microscopic point will obviously require the expenditure of less energy in parting the air during flight than a projectile having a blunt 30 point, yet the sharp point of such a projectile is apt to become broken or bent during handling or transportation of ammunition, thereby producing a defective round. Furthermore, a projectile having a sharp point is not only somewhat dangerous to handle but is likely to jam in the mechanism of repeating or self-loading arms. As a 35 result, projectiles of the type herein shown are usually made with a nose having a blunt point.

In order to provide a sharp pointed projectile 50 which can be handled, manipulated and loaded into the cartridge case without danger of breaking, bending or injuring the point, and which, when so loaded into the cartridge case, will provide a round of ammunition which is similar in 55 shape and appearance to a standard round and

can thus be readily loaded into cartridge belts, cartridge magazines, guns, etc., interchangeably with ordinary standard ammunition, I have provided a projectile in which the point or tip of the nose is extensible and retractable and in which such sharp pointed tip is normally situated within the body of the projectile and is thus protected, but is automatically projected beyond the body when the gun is fired, thereby providing the projectile with a sharp pointed nose which enables it to more easily part the air, thus conserving energy during its entire flight. My improved projectile, therefore, has the capacity of automatically changing its shape to one having an improved ballistic form.

My improved projectile 2 is formed with a body portion 8 and the pointed nose portion 9. The base part 10 of the nose portion 9 is formed integral with the body 8 and presents a convex exterior curvature 11 which may have a head radius or ogive of any desired calibers. The tip or point of the nose portion 9 is indicated at 12, and the exterior surface of such tip portion is preferably concavely curved, as shown at 13, such concave curvature being tangential to and merging into the convex curvature 11. This tip portion 12 of the nose may be rigid with the base portion 10 but in the preferred embodiment of my invention, such tip portion 12 is constructed to be retracted into the base portion of the nose, as shown in Fig. 2, in which position the sharp point 14 of the nose tip is protected so that it cannot be injured or broken during any handling or transportation of the cartridge, and so that it will not interfere in any way with the operation of loading the ammunition into the cartridge belts, cartridge containers, guns, etc. A round of ammunition loaded with a projectile embodying my invention can be handled in the same way as standard ammunition of like caliber, and by the same mechanism used in handling such standard ammunition, and can be used in any gun the same as standard ammunition.

My improved projectile, however, is so constructed that the pointed tip 12 of the nose may be projected forwardly beyond the base of the nose into operative position, shown in Fig. 3, thereby changing the shape of the projectile to one having an improved ballistic form.

One way in which this may be accomplished is by providing the body 8 of the projectile with an axial bore 15 and forming the tip portion 12 of the nose with a stem 16 which occupies said bore and extends through the projectile. The stem 16 and tip portion 12 thus form a needle-like member occupying the bore of the projectile body. The end of the stem opposite the nose is shown as having a head 17 shaped to fit a seat 18 formed in the base of the projectile body 8, said head, when seated, functioning as a valve.

When the projectile 2 is loaded into the cartridge case 1, the tip 12 of the nose is in its retracted position with the head 17 spaced from the base or tail end of the projectile body 8. When the cartridge is fired or detonated, the pressure developed by the explosive charge serves not only to project the projectile 2 through and from the barrel of the gun, but it also serves early in the pressure cycle to force the stem 16 and the tip portion 12 of the nose forwardly, thereby to project such tip portion beyond the base of the nose, and at the same time to seat the valve head 17 onto the seat 18, as shown in Fig. 3. The effective pressure on the head 17 which causes the stem 16 to move forwardly in the pro-

jectile is the pressure developed within the cartridge case by the ignition of the explosive charge 7 (which is not infrequently as high as fifty thousand pounds per square inch) against an area equal to the cross sectional area of said stem 16, this being the difference between the areas of the rear face and the front face of the head 17. When the gun is fired, therefore, the shape of the projectile is automatically changed from one having a standard form to one having a sharply pointed nose with an improved ballistic coefficient. According to the laws of physics, a slender needle-like element such as the stem 16 will have, for its weight, greater penetrating power than an article of larger transverse dimension and hence when a projectile having the construction herein shown strikes an object, the inertia of the stem 16 will tend to force the stem forwardly ahead of the projectile and thus causing it to penetrate the object to a greater extent than the body of the projectile. Under some circumstances this will be sufficient to strip the head from the stem 16 and hence my projectile will have greater penetrating powers than an ordinary projectile of the same general shape.

I will preferably provide means for closing the cavity in the nose of the projectile which exists when the nose tip 12 is in its retracted position shown in Fig. 2 so as to prevent the entrance of dirt or foreign matter into said cavity. Any suitable way of accomplishing this end may be employed without departing from the invention. One simple way is to fill the space 19 around the pointed end of the nose tip with some material, such as graphite, wax, etc., which will be easily forced out of the bore 15 when the nose tip is projected and will fall away from the projectile.

Another efficient way of closing the open front end of the nose is to crimp or spin the sharp edges 27 of the projectile inwardly, as shown in dotted lines, Fig. 8. The force with which the nose tip is projected forwardly when the projectile is discharged will cause the nose tip 12 to bend the edges 27 backwardly to their normal position, during which operation said inturned edges will hug the sides of the nose tip and will form with the projected tip a smooth exterior surface on the projectile. In Figs. 4 and 5, I have illustrated an embodiment of the invention wherein the projectile is provided with a tapered tail extending beyond the base of the body portion, said tail forming with the base a rearwardly facing shoulder. This construction not only reduces the vortex at the rear of the projectile during its flight, but it provides means whereby the flow of air around the travelling projectile has a propelling effect thereon which partially counteracts and makes up for the loss of energy due to the parting of the air in the forward movement of the travelling projectile.

In Figs. 4 and 5 the projectile is shown at 2a, and it is similar in shape to the projectile 2, shown in Figs. 1 to 3, it having the central bore 15a in which is received the stem 16a carrying at its outer end the nose tip 12a, the sides of which are concavely curved, as shown at 13a, thereby making the tip with an extremely sharp point 14a. In the embodiment shown in Figs. 4 and 5, a streamlined tail member 21 is secured to the end of the stem 16a, the forward face 26 of which tail member is adapted to seat against the seat 18a in the base of the projectile when the nose tip 12a is projected forwardly. The tail 21 has a streamlined shape, the body of the tail having the convexly curved portion 22 which

merges into the concavely curved tip portion as shown at 23, thereby to produce a sharp point 24.

When the projectile is loaded into the cartridge case 1, the nose tip 2a is in its retracted position shown in Fig. 4, and the tail 21 will be separated from the base of the projectile, also as shown in Fig. 4. When the gun is fired, the pressure developed in the cartridge case forces the tail portion 21 and stem 16a forwardly into a position in which the face 26 of the tail 21 seats against the seat 18a, and the nose tip 12a is projected beyond the body of the projectile. The diameter of the tail 21 is less than that of the projectile 8a at its base and consequently when the tail portion 21 is seated against the base of the projectile, as shown in Fig. 5, there will be provided an annular rearwardly facing shoulder 28. When the projectile is in flight, there will be a flow of air along the surface of the projectile, indicated by arrows *a* in Fig. 5, and as this air passes over the shoulder 28, it will impinge against the tapered tail 21, as indicated by the arrows *b* thus producing a squeezing action on the tapered tail which produces a propelling effect on the projectile much in the same way as squeezing of a watermelon seed between one's thumb and forefinger will produce a propelling action thereon.

As stated above, the presence of the streamlined tail 21 reduces the vortex at the rear of the projectile, and consequently reduces the drag thereon which the vortex produces. In addition, the squeezing effect on the tapered tail of the air flowing over the shoulder 28 has a propelling effect on the projectile which counteracts to some extent the head resistance, and as a result a projectile embodying my invention will have a much higher sustained velocity than similar projectiles now in use, though the muzzle velocities are identical. The concave curvature 13 and 13a at the nose tip of the projectile provides a shape which enables the projectile to pierce the air with a minimum of head resistance and directs the air gently outwardly, thereby reducing the skin friction of the air flowing over the body of the projectile, and this is a factor in maintaining its spin and hence its gyroscopic stability.

The stem 16 has a sufficiently tight fit in the bore 15 so as to prevent said stem from moving inwardly or outwardly from its normal retracted position during any handling or transportation of the projectile, and in order to provide for this, said stem is made with a degree of resiliency and also slightly curved, as indicated in Fig. 7 (although Fig. 7 illustrates the curvature exaggerated), so that when the stem is inserted into the bore 15 of the projectile, the consequent straightening of the stem will produce sufficient friction between it and the wall of the bore to securely hold the stem from premature backward or forward movement. The amount of friction between the stem 16 and the wall 15 can be varied by varying somewhat the normal curvature of said stem, and in this way the point in the pressure cycle at which the head 17 or 22 seats against the seat 18 or 26 may be controlled. It is desirable that this seating of the head should occur before the projectile has moved any appreciable distance up the barrel.

Experiments I have made have shown a projectile embodying my invention will make less noise during flight than a standard projectile of similar caliber head. The creation of sound waves by a moving object necessarily involves the expenditure of energy, and as sound waves

of less intensity are produced by a projectile embodying my invention than are produced by a similar projectile of standard form, it follows that less of the energy stored up in a projectile embodying my invention when it is fired is dissipated in producing sound waves, and consequently a greater proportion of such energy is available for continuing the flight of the projectile.

- 10 A projectile embodying my invention may have the shape and contour of any standard projectile, and hence a cartridge loaded with my improved projectile can be used in any existing firearms. In fact, a cartridge case loaded with 15 my improved projectile has the same appearance as the same cartridge case loaded with any standard projectile. My invention has the further advantage that it is possible to convert standard projectiles into projectiles embodying my invention by simply providing such standard projectiles with the axial bore 15 and valve seat 18, and then assembling with such projectiles the nose tip and stem embodying my invention.

Experiments I have made have indicated that 25 a projectile embodying my invention having the rearwardly projecting tapered tail portion which is smaller in diameter than the body portion, and forming therewith a rearwardly facing shoulder will have a reduced yaw or spiral motion 30 after it leaves the barrel of the gun as compared with standard projectiles and will, therefore, "go to sleep" at a much earlier point in its trajectory than such standard projectiles.

While I have illustrated herein my invention 35 as embodied in a projectile seated in a cartridge case and constructed so that it will automatically change its shape to one having an improved ballistic form between the time it is loaded into the gun and the time it is discharged 40 therefrom, yet certain features of the invention are applicable to projectiles which are not seated in cartridge cases and in which the change of shape may be accomplished manually and at the time the projectile is loaded into the gun.

45 It will be understood, therefore, that the invention is not limited to the construction herein shown but is capable of being embodied in projectiles of various types, formation and sizes.

- I claim:
- 50 1. A projectile for guns having a body provided with a tapered nose portion and a blunt base, and having an axial bore therethrough, a stem movable in said bore between a retracted and a forward operative position, said stem having at its forward end a tapered pointed nose tip and at its rear end a rearwardly streamlined tail, said stem normally occupying the retracted position with the nose tip within the body and the tail spaced from the blunt base of the body 55 but adapted to be projected to operative position with the surface of the nose tip projecting beyond the body and forming a continuation of the surface thereof, and with the tail abutting the base of the body and forming a shouldered continuation thereof.

2. A projectile for guns having a body portion provided with an axial bore, a needle-like member with a pointed end in said bore and movable therein from a retracted position in which the pointed end is located within the bore to an operative position in which the pointed end projects beyond the body and constitutes the tip of the nose of the projectile, the rear end of said needle-like member being exposed to the pressure developed within the gun when it is

fired whereby such pressure moves said member from its retracted position to its operative position, and means to limit the forward movement of said member and to seal said bore when said member is in its forward position.

3. A projectile for guns having a body portion provided with an axial bore, a needle-like member with a pointed end in said bore and normally occupying a position in which the pointed end is located within the bore, said needle-like member having its rear end exposed to the pressure developed within the gun when it is fired and being adapted to be moved by such pressure to an operative position in which the pointed end projects beyond the body and constitutes the tip of the nose of the projectile, and means to limit the forward movement of the needle-like member.

4. A projectile for guns having a body provided with an axial bore, a needle-like member having a pointed end located in said bore and normally occupying a retracted position in which the pointed end is situated within the bore at the nose end of the projectile, said needle-like member being adapted to be advanced in the bore to operative position in which the pointed end thereof projects beyond the body and constitutes the tip of the nose of the projectile, and a valve head secured to the rear end of the needle-like member and adapted to seat against the base of the body when said member is in its operative position.

5. A projectile for guns having a body provided with an axial bore, a needle-like member having a pointed end located in said bore and normally occupying a retracted position in which the pointed end is situated within the bore at the nose end of the projectile, said needle-like member being adapted to be advanced in the bore to operative position in which the pointed end thereof projects beyond the body and constitutes the tip of the nose of the projectile, and a pointed tail member secured to the rear end of said needle-like member and adapted to seat against the base of the projectile body when said needle-like member is in its operative position.

6. A projectile for guns having a body provided with an axial bore, a needle-like member having a pointed end located within said bore and normally occupying a retracted position in which the pointed end is situated within the bore at the nose end of the projectile, said needle-like member being adapted to be advanced in the bore to operative position in which the pointed end thereof projects beyond the body and constitutes the tip of the nose of the projectile, and a pointed tail member secured to the rear end of said needle-like member and adapted to seat against the base of the projectile body when said needle-like member is in its operative position, said tail member having a diameter smaller than that of the base end of the projectile whereby when the needle-like member is in its operative position, said tail member forms with the projectile body a rearwardly facing shoulder.

7. A projectile for guns comprising a body portion provided with an axial bore, a needle-like member located within said bore and having a pointed end, said member being movable relative to the body between a retracted position in which the pointed end is located within the bore to an operative position in which the pointed end projects beyond the body and constitutes the tip of the projectile nose, said needle-like member having a valve head adapted to engage the base end

of the body when said member is in its operative position.

8. A projectile comprising a body portion having a bore extending axially therethrough, a needle-like member in said bore having a pointed front end, and a valve head on said needle-like member at the rear end thereof, said needle-like member being movable forwardly in the bore to seat the valve against the base of the body and to project the pointed end beyond the body, in which position it forms a pointed tip for the projectile nose.

9. A projectile for guns comprising a body having a tapered nose portion and provided with an axial bore, a needle-like member fitting said bore and provided with a pointed end located within said bore, the material of the nose portion at the end of the bore being spun inwardly to close the bore, said needle-like member being movable in the bore to project the pointed end through the closed end of the bore and into a position in which it forms the nose tip of the projectile.

10. A projectile for firearms in which the tip portion of the nose is movable axially of the body portion between a retracted position in which it is located entirely within the body of the projectile and an operative position in which it is located beyond the body portion, in which latter position it forms the tip of the projectile nose, and means responsive to the pressure developed within the barrel of the firearm when the latter is fired to move said tip portion from its retracted position to its operative position, the base of the nose portion being convexly curved in the direction of its length and the movable tip portion of the nose being concavely curved in the direction of its length.

11. A projectile for firearms having a body provided with an axial bore extending therethrough, a stem having a pointed end slideable in said bore and free to move from a retracted position in which its pointed end is located within said bore and is thus protected to an operative position in which said pointed end projects beyond the body and forms the tip portion of the projectile nose, the rear end of the stem being exposed to receive the pressure developed within the gun when the latter is fired.

12. A projectile as described in claim 11 in which the exterior surface of the projected portion of the stem when the latter is in its forward operative position forms an unbroken continuation of the surface of the projectile body.

13. A projectile for firearms having a body provided at its forward end with an axial bore, and a member in said bore having a pointed outer end, said member being free to move in the bore from a retracted position to an operative forward position in which the pointed end projects beyond the body portion and forms the tip portion of the projectile nose, said body and said member having co-operating parts which limit the forward movement of the member, said projectile having provision for subjecting the rear end of said member to the pressure developed within the gun when it is fired, whereby said member is held by such pressure in its forward operative position during the traveling movement of the projectile through the barrel of the firearm.

14. A projectile for firearms having a body provided at its forward end with an axial bore, and a member having a pointed outer end located in said bore, said member being free to move in the bore from a retracted position to an opera-

tive forward position in which the pointed end projects beyond the body portion and forms the tip portion of the projectile nose, said body and said member having cooperating parts which limit the forward movement of the member, said projectile having provision for subjecting the rear end of said member to the pressure developed within the gun when it is fired, whereby said member is held by such pressure in its forward operative position during the traveling movement 10

of the projectile through the barrel of the fire-arm, the pointed end of said member which is exposed when it is in its forward operative position having a longitudinal curvature which merges into the longitudinal curvature of the body adjacent the projected portion of said member, whereby when said member is in its forward operative position the ballistic characteristics of the projectile are improved.

GEORGE NORMAN ALBREE.
